The ornamental design for a mobile phone, as shown and described.

DESCRIPTION

FIG. 1 is a front perspective view of a mobile phone in accordance with the present application;

FIG. 2 is a rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a front perspective view of another embodiment of a mobile phone in accordance with the present application;

FIG. 10 is a rear perspective view thereof;

FIG. 11 is a front view thereof;

FIG. 12 is a rear view thereof;

FIG. 13 is a left view thereof;

(Continued)

FIG. 14 is a right view thereof;
FIG. 15 is a top view thereof;
FIG. 16 is a bottom view thereof;
FIG. 17 is a front perspective view of another embodiment of a mobile phone in accordance with the present application;
FIG. 18 is a rear perspective view thereof;
FIG. 19 is a front view thereof;
FIG. 20 is a rear view thereof;
FIG. 21 is a left view thereof;
FIG. 22 is a right view thereof;
FIG. 23 is a top view thereof;
FIG. 24 is a bottom view thereof;
FIG. 25 is a front perspective view of another embodiment of a mobile phone in accordance with the present application;
FIG. 26 is a rear perspective view thereof;
FIG. 27 is a front view thereof;
FIG. 28 is a rear view thereof;
FIG. 29 is a left view thereof;
FIG. 30 is a right view thereof;
FIG. 31 is a top view thereof;
FIG. 32 is a bottom view thereof;

FIG. 33 is a front perspective view of another embodiment of a mobile phone in accordance with the present application;
FIG. 34 is a rear perspective view thereof;
FIG. 35 is a front view thereof;
FIG. 36 is a rear view thereof;
FIG. 37 is a left view thereof;
FIG. 38 is a right view thereof;
FIG. 39 is a top view thereof;
FIG. 40 is a bottom view thereof;
FIG. 41 is a front perspective view of another embodiment of a mobile phone in accordance with the present application;
FIG. 42 is a rear perspective view thereof;
FIG. 43 is a front view thereof;
FIG. 44 is a rear view thereof;
FIG. 45 is a left view thereof;
FIG. 46 is a right view thereof;
FIG. 47 is a top view thereof; and,
FIG. 48 is a bottom view thereof.

The broken lines showing of portions of the mobile phone are for the purpose of illustrating the portions of the mobile phone and form no part of the claimed design.
